LUGGAGE HANDLE OR THE LIKE

Simon Javkin, 160 West End Ave.,
New York, N.Y. 10023

Filed Nov. 18, 1969, Ser. No. 20,163

Term of patent 14 years

Int. Cl. D8—07

U.S. Cl. D8—154

FIG. 1

FIG. 2

FIG. 3

FIG. 4

FIG. 5

FIG. 1 is a front elevational view of a luggage handle or the like embodying my new design;

FIG. 2 is a side elevational view thereof; the opposite side being identical;

FIG. 3 is a top plan view thereof;

FIG. 4 is a bottom plan view thereof; and

FIG. 5 is a rear perspective view thereof.

I claim:

The ornamental design for a luggage handle or the like, as shown and described.
